CHICK FEED TROUGH

Application filed May 11, 1928. Serial No. 277,070.

This invention relates to feed troughs for small chickens or chicks and has for an object to provide an improved construction where access to the feed may be readily had while the chicks are prevented from entering the trough.

Another object of the invention is to provide a chick feeding trough wherein a rotatable protecting bar is positioned across the trough.

A still further object, more specifically, is to provide a trough with the parts pressed from sheet metal so as to interlock when assembled.

15 In the accompanying drawing,—

Figure 1 is a perspective view of a chick feed trough disclosing an embodiment of the invention;

Figure 2 is an enlarged fragmentary sectional view through Figure 1 approximately on line 2—2;

Figure 3 is an enlarged transverse sectional view through Figure 1 on line 3—3;

Figure 4 is an inside end view on an enlarged scale of one of the end members shown in Figure 1.

Referring to the accompanying drawing by numerals, 1 and 2 indicate end members and 3 a connecting trough-body. The end members 1 and 2 are identical in structure, and therefore, the description of 1 will apply to both. As shown in Figure 2, end member 1 is provided with a turned-in flange 4 presenting a supporting foot and a groove 5 for receiving the end of the trough-body 3. In order to hold the parts together after assembled, as shown in Figure 2, solder 12 is applied to the ends of the trough 3 so as to secure the same in the respective grooves

40 5. By pressing these grooves in the end members upstanding exterior beads are presented which provide stiffening means for bracing the respective parts. At the upper part of the end member 1 a portion has been 45 cut and bent to present a horizontal section 6 which is bent a second time to form the upstanding abutment 7. The abutment 7 is provided with a pressed boss or portion 8 presenting a journal pin for the tube 9. 50 The tube 9 is adapted to be rotatably mounted

on the journal pins or abutments 8. The ends 1 and 2 and the body 3 are preferably made from sheet metal, and the tube 9 is also preferably made from sheet metal, although it could be made from an ordinary pipe. 55 From Figure 3 it will be noted that the trough-body 3 has the upper edges curled, as indicated at 10 and 11. This makes a smooth surface over which the chicks bend when feeding from the trough. The space between the bent edges 10 and 11 and the pipe 9 is ample to permit the passage of the heads of the chicks but will not permit the bodies to pass. In this way the chicks are prevented from entering the trough and by 60 reason of the rotatable mounting of pipe 9 the chicks cannot roost thereon as the movement of the pipe would prevent this action.

What I claim is:—

1. In a chick feed trough, an end member 70 comprising a single sheet of metal formed with a pressed-out portion presenting a trough-receiving groove and a pressed-out tongue having an offset portion, said offset portion being formed with an integral 75 pressed-out boss acting as a projecting journal pin.

2. A chick feed trough, comprising a body of sheet metal, a pair of sheet metal ends formed with grooves for receiving the ends 80 of said body, each of said ends having a pressed-out offset portion presenting a shoulder, each of said pressed-out portions having a pressed-out boss acting as a journal pin, and a tube loosely and rotatably 85 mounted on said pins, said tube extending longitudinally of said body and substantially centrally thereof at a point above the body.

Signed at New York, in the county of New York and State of New York, this 8th 90 day of May, A. D. 1928.

WALTER H. COLLINS.
